INVENTOR

Hector Falletta
BY
A. Martell
ATTORNEY.

UNITED STATES PATENT OFFICE.

HECTOR FALLETTA, OF LOS ANGELES, CALIFORNIA.

ELLIPSOGRAPH.

Application filed January 26, 1924. Serial No. 688,680.

To all whom it may concern:

Be it known that I, HECTOR FALLETTA, a citizen of Italy, residing at Los Angeles, in the county of Los Angeles and State of California, have invented new and useful Improvements in Ellipsographs, of which the following is a specification.

My invention relates to drafting instruments, and the general object thereof is to provide an improved instrument for drawing ellipses of various forms and sizes.

A more particular object is to provide an instrument of the character stated which will be simple in construction and accurate and efficient in operation.

Other objects and advantages will appear hereinafter and while I show herewith and will describe a preferred form of construction, I desire to be understood that I do not limit my invention to such preferred form but that various changes and adaptations may be made therein without departing from the spirit of my invention as herein-after claimed.

Referring to the annexed drawing which forms a part of this specification:

Fig. 1 is a plan view of my instrument shown in the act of drawing an ellipse.

Fig. 2 is a side elevation of my instrument as shown in Fig. 1.

Fig. 3 is an edge view of the lower portion of one leg of the foci dividers of my instrument.

Fig. 4 is a side view of said lower portion of said leg.

Fig. 5 is a side elevation of the marker and chain carrier.

Fig. 6 is a longitudinal section of the marker and chain carrier.

Fig. 7 is a view of the lower portion of the marker and chain carrier.

Fig. 8 is a horizontal section of my instrument taken on line 8-8 of Fig. 2.

My instrument comprises a foci element such as a pair of ellipse foci dividers 1, a marker and guide chain carrier 2, and a guide chain 3. Said dividers comprise a pair of legs 4 pivoted together at their upper ends by pivot 5, a handle 6 pivoted to said legs by said pivot, and feet 7 pivoted to 8 to the lower ends of said legs. Each

leg 4 may be made in a plurality of sections, such as an upper section 9 and a lower section 10, which sections are joined together by a telescopic joint 11 including a set screw 55 12 for securing said sections together.

Each foot 7 has a flat tread plate 13, which rests upon the surface upon which the ellipse is to be drawn and support the dividers. Upstanding foci pins 14 are formed on the 60 plates 13 and heads 15 are formed on the upper ends of said pins.

Depending points 16 are formed on the extremities of the tread plates 13 for sticking into the surface on which the ellipse is 65 to be drawn for properly holding the dividers 1 on said surface with the foci pins 14 properly spaced to determine the foci of the ellipse to be drawn. The marker and guide chain carrier 2 comprises a barrel 17 provided with a longitudinal bore 18 extending therethrough and formed in two sections 19 and 20 coupled together by a swivel coupling 21 and a chain reel 22 journaled in the upper end of said barrel. The coupling 75 21 comprises a male member 23 and a female member 24.

The male coupling member 23 is threaded to screw into a threaded socket 25 in the upper end of the lower marker member 19, 80 and said coupling member has an external annular flange 26 formed on the upper end thereof. The female coupling member 24 is internally threaded to screw onto the reduced lower threaded end 27 of the upper 85 marker member 20.

The lower end of the female member 24 is closed by a wall 28 in which is provided a central opening through which extends the male member 23 with the flange 26 thereof 90 engaging the inner and upper side of said wall 27. The coupling 21 permits the lower marker member 19 to turn with relation to the upper marker member 20. The reel 22 is secured on a shaft 30 journaled in the 95 upper end of the marker member in bearings 31. A ratchet wheel 32 is secured on one end of shaft 30 at one side of the marker and a thumb wheel 33 is secured on the other end of said shaft at the other side of the 100 marker. A pawl 34 is pivoted on the upper part of the mark at the side at which the

ratchet 32 is mounted, which pawl engages said ratchet, there being a handle 35 on said pawl for disengaging the same from said ratchet and a spring 36 secured to the marker 5 engages said handle and normally maintains said pawl in engagement with said ratchet and prevents rotation of reel 22 and unwinding of the chain 3 therefrom, one end of the chain being wound on said reel. Said chain 10 extends downwardly through the bore 18 and its other end is secured to an eye 37 on the lower pointed end 38 of the marker. A screw clamp 40 is formed on the lower member 19 of the marker 2 on the side thereof 15 opposite the side on which the eye 37 is formed in which clamp either a pencil 41 or a pen 42 is clamped at its upper end 43 or 44, so that the point 45 or 46 of said pencil or said pen rests adjacent the point 38 20 of the marker and on the side of said point opposite the side on which the eye 37 is formed.

In operation a sufficient amount of chain 3 is let off the reel 22 to form a loop 50, 25 which is extended around the foci pins 14 with the point 45 or 46 of the pencil 41 or pen 42 outside said loop, the dividers 1 being adjusted and placed on the surface on which the ellipse is to be drawn with the 30 foci pins 14 properly positioned for the ellipse desired, and the points 16 stuck into said surface and holding said dividers in such position.

The loop 50 may be adjusted to the proper 35 size for the desired loop by turning the reel 22 by the thumb wheel 33 and winding up the chain on said reel or unwinding the chain therefrom, the pawl 34 being released from the ratchet 32 when the reel is turned 40 to unwind the chain to enlarge the loop.

The marker 2 being held by its upper member 20, it is held outward as far as possible with the chain 3 taut and is carried around the foci pins 14 until the complete 45 ellipse 51 is drawn about said foci, the coupling 21 permitting the lower marker member 19 to turn with relation to the upper member 20 as the marker travels around said foci pins, thus facilitating the drafting 50 of the ellipse.

Having described my invention, I claim:

1. An instrument for drawing ellipses comprising a pair of dividers having legs in combination with a marker holder and a 55 guide chain, a foot on each leg of said dividers, a fixing point and a focus pin on each of said feet, a swivel joint in said marker holder, a marker fixed in said marker holder below said swivel joint and 60 adjustable means for attaching one end of said chain to said marker holder whereby the chain may be looped around said focus pins to serve as a guide for said marker in tracing ellipses of different forms and 65 sizes.

2. An instrument for drawing ellipses comprising in combination a pair of dividers having legs, a marker holder and a guide chain, a foot terminating each leg of said dividers, a fixing point and a focus pin on each of said feet, a screw clamp on said marker holder adapted to hold a marker, a marker held in said screw clamp, a swivel joint in said marker holder above 75 said screw clamp and means on said marker holder for adjustably holding one end of said chain whereby when said chain is looped around said focus pins while the other end thereof is attached to said holder whereby said marker may be guided around said 80 focus pins by said chain to trace an ellipse.

3. An instrument for drawing ellipses comprising in combination a pair of dividers having jointed legs, an elongated marker holder with a swivel joint somewhat 85 below its middle point and a chain attached to said marker holder; a foot terminating each leg of said dividers, a fixing point and a focus pin on each of said feet; a screw clamp on said marker holder below said 90 swivel joint, a marker held by said clamp, an eye on the lower end of said marker holder for attaching one end of said chain, a reel on the upper end of said marker holder for winding up the other end of said 95 chain, a ratchet on said reel and a pawl on said marker holder adjacent thereto, for holding said reel from unwinding.

4. An instrument for drawing ellipses comprising a pair of dividers with jointed 100 legs in combination with a tubular marker holder and a guide chain carried by the marker holder; feet terminating the legs of said dividers, a fixing point and a focus pin on each of said feet, a swivel joint in said 105 marker holder which divides it into an upper and a lower section, the upper section being adapted to be held by an operator and the lower section being adapted to carry a marker, a marker mounted in the lower section 110 of said marker holder, a detent controlled reel mounted in the upper section of said marker holder, said reel being adapted to wind up one end of said chain, the other 115 end thereof being attached to the lower section of said marker holder adjacent said marker point, whereby said chain may be looped around said focus pins to guide said marker in tracing an ellipse.

5. An instrument for drawing ellipses, 120 comprising a pair of dividers with jointed legs terminating in flat feet, a fixing point and a focus pin on each of said feet; a marker holder, including an upper and a lower section, a swivel joint connecting the 125 upper and lower sections of said marker holder; a screw clamp on said lower section; a marker held by said screw clamp; a pawl and ratchet controlled reel journaled in the upper end of said upper section; and 130

a guide chain secured at one end to the lower end of the lower section of said marker holder, adjacent the point of said marker, and extending in a loop around said focus pins back to the point of attachment and upwardly through a central bore in said lower and upper sections and swivel joint

of said marker holder, with its other end attached to said reel, said chain loop being adapted to travel around said focus pins 10 while the marker moves on the outer side thereof in tracing an ellipse.

HECTOR FALLETTA.
